DOOR ALARM BOLT

Charles R. Suska, Roxbury, and Peter Thomson, Fairfield,
Conn., assignors to The Stanley Works, New Britain,
Conn.

Filed Sept. 9, 1971, Ser. No. 179,256

Term of patent 14 years

Int. Cl. D8—07; D29—02
U.S. Cl. D8—131

FIG. 1

FIG. 2

FIG. 4

FIG. 1 is a perspective view looking downwardly towards the front of a door alarm bolt showing our design;

FIG. 2 is a left side elevational view of the door alarm bolt shown in FIG. 1;

FIG. 3 is a rear elevational view of the door alarm bolt shown in FIG. 1; and

FIG. 4 is a bottom plan view of the door alarm bolt shown in FIG. 1.

We claim:

The ornamental design for a door alarm bolt, as shown.
